DEVICE FOR USE IN UNCOUPLING DRILL STEELS

John C. Curtis, Newport, N.H., assignor to Joy Manufacturing Company, Pittsburgh, Pa., a corporation of Pennsylvania

Filed Nov. 13, 1957, Ser. No. 696,250

6 Claims. (Cl. 175—223)

This invention relates to uncoupling devices and more particularly to a device for use in uncoupling the sections of an elongated rock drill steel or the like.

In hammer rock drills such as are used in deep hole drilling the drill steel is relatively elongated and is made up of a series of drill steel sections detachably connected together by couplings. On removal of the drill steel from a drilled hole considerable difficulty has heretofore been encountered in releasing the couplings to disconnect the drill steel sections.

The present invention resides in an improved device for use in uncoupling drill steels whereby the sections of an elongated sectional drill steel or the like may be readily and quickly uncoupled. This is accomplished by connecting a coupling element of the drill steel to a stationary part of the rock drill so that an adjacent drill steel section may be rotated in a suitable manner to uncouple the joint. In accordance with the present invention the coupling is provided with means having interlocking connection with an element of the drill steel centralizer of the rock drill so that the coupling element may be held against rotation during release of the joint.

An object of the present invention is to provide an improved means for use in uncoupling a sectional rock drill steel. Another object is to provide an improved means for use in uncoupling a sectional drill steel wherein a coupling element of the drill steel is engaged with a part of a rock drill and thereby held against rotation during turning of an adjacent drill steel section to release the joint. A further object is to provide an improved device for use in uncoupling rock drill steels wherein a coupling element is interlocked with an element of the drill steel centralizer of the rock drill for holding the coupling element against rotation thereby to enable an adjacent drill steel section to be rotated to uncouple the joints. Yet another object is to provide an improved coupling element for rock drill steels. Other objects and advantages of the invention will be clearly apparent to those skilled in the art.

In the accompanying drawing there are shown for purposes of illustration one form and a modification which the invention may assume in practice.

In this drawing:

Fig. 1 is a fragmentary side view of a hammer rock drill of the guide frame mounted type with which the present invention is associated, showing the drilling tool, sectional drill steel and drill steel centralizer.

Fig. 2 is an enlarged longitudinal section taken through the centralizer on line 2—2 of Fig. 1, showing the centralizer bushing with which a coupling element has interlocking engagement during uncoupling of a joint.

Fig. 3 is an enlarged cross section taken through the drill steel centralizer and showing the interlocking connection between the centralizer bushing and a coupling element.

Fig. 4 is a detail view showing a modified interlocking connection between a coupling element and the centralizer bushing.

2

Fig. 5 is a detail section taken on line 5—5 of Fig. 4, illustrating structural details.

The invention is associated with a hammer rock drill of a conventional design comprising a guide frame 1 along which a hammer drilling tool 2 is guided for movement toward and from the face of the work. The drilling tool embodies a conventional pressure fluid hammer motor 3 for percussively actuating and rotating a drill steel 4. The drilling tool has a usual chuck 5 for receiving the shank 6 of the drill steel and lugs 7 on the drill steel shank are adapted to have interlocking connection with an element of the chuck for locking the drill steel shank within the chuck during the drilling operation. The drill steel is relatively elongated and carries a usual drill bit 8 for drilling relatively deep holes and comprises a series of drill steel sections 9 threaded at 10 for threaded engagement with internally threaded coupling elements 11. Carried at the forward portion of the guide frame is conventional drill steel centralizer 12 for guiding the drill steel to center the drill bit during starting or "spotting" of a hole.

The drill steel centralizer may assume various forms but herein, for illustrative purposes, comprises cooperating pivoted parts in the form of swingable guide arms 13 pivoted at 14 on the guide frame and each carrying a semi-circular bearing or bushing portion 15 which, when the centralizer arms are closed as shown in full lines in Fig. 3, embraces the body of the drill steel just rearwardly of the drill bit. The semi-circular bushing parts are positioned by dowels 16 and detachably secured to the arms by bolts 17 (Fig. 2). The arms of the drill steel centralizer may be swung wide apart, as indicated in dotted lines in Fig. 3, so that the hammer drilling tool 2 may be advanced along the guide frame between the arms.

In the improved device for use in uncoupling drill steels each coupling element 11 is transversely grooved or notched at 19 and the two semi-circular halves of the bushing of the drill steel centralizer have projections 20 which interlock with the coupling element for holding the latter against rotation. If desired, the bushing may be notched and the cooperating lugs may be formed on the coupling element 11. The drill steel shank 6, during breaking of the joints of the drill steel, is released from locking engagement with the chuck of the drilling tool, as shown in Fig. 1, so that while the rear end of the drill steel is supported within the chuck it is free to be rotated. When the coupling element is so held against rotation a conventional pipe wrench or other turning tool 21 is connected to the adjacent drill steel section so that the latter may be rotated to uncouple the threaded joint. Each coupling element of the sections of drill steel is similarly notched for interlocking engagement with the drill steel centralizer.

In Figs. 4 and 5 a modified interlocking connection between a coupling element and the centralizer bushing is disclosed. In this construction the coupling element is externally of polygonal, desirably of hexagonal shape as at 22 and the semi-circular parts of the bushing cooperate to provide a hexagonal socket 23 for receiving the coupling element for locking the latter against rotation.

While the device as disclosed is used to uncouple the joints of a sectional drill steel it may also serve to couple the joints. Evidently the invention may be associated with tools of other types and in lieu of a sectional drill steel other types of jointed rods may be employed.

As a result of this invention an improved device for use in uncoupling drill steels is provided whereby the sections of an elongated rock drill steel or the like may be easily and quickly uncoupled. By the provision of the interlocking connection between the coupling element of a joint

to be disconnected with a part of the rock drill such as the drill steel centralizer a coupling element may be readily held against rotation while the adjacent drill steel section may be rotated to release the joint. The device for use in uncoupling drill steels is relatively simple and rugged in design and may be incorporated in a conventional rock drill with a minimum of change. Other advantages will be clearly apparent to those skilled in the art.

While there are in this application specifically described one form and a modification which the invention may assume in practice, it will be understood that this form and modification of the same are shown for purposes of illustration and that the invention may be further modified and embodied in various other forms without departing from its spirit or the scope of the appended claims.

What I claim as new and desire to secure by Letters Patent is:

1. In a rock drill having a frame which supports a drill steel centralizer member having open and closed positions which is closed during the starting of drilling to axially guide an elongated sectional drill steel the adjacent sections of which drill steel are joined together by coupling members, respectively, the improvement comprising, locking means on said centralizer member and cooperating locking means on said respective coupling members to provide an interlock between the centralizer member and a selected one of said coupling members when said centralizer member is closed and said locking means are engaged to hold said one coupling member from rotation so that a drill steel section is rotatable relative to said one coupling member to release the joint between adjacent drill steel sections coupled by said one coupling member.

2. In a rock drill having a frame which supports a drill steel centralizer member having open and closed positions which is closed during the starting of drilling to axially guide an elongated sectional drill steel the adjacent sections of which drill steel are joined together by coupling members, respectively, the improvement comprising, locking means on said centralizer member and cooperating locking means on said respective coupling members to provide an interlock between the centralizer member and a selected one of said coupling members when said centralizer member is closed and said one coupling member is moved axially so that said locking means are engaged to hold said one coupling member from rotation so that a drill steel section is rotatable relative to said one coupling member to release the joint between adjacent drill steel sections coupled by said one coupling member.

3. In a rock drill having a frame which supports a drill steel centralizer member having open and closed positions which is closed during the starting of drilling to axially guide an elongated sectional drill steel the adjacent sections of which drill steel are joined together by coupling members, respectively, the improvement comprising locking means on said centralizer member and cooperating locking means on said respective coupling members to provide an interlock between the centralizer member and a selected one of said coupling members when said centralizer member is closed and said locking means are engaged to hold said one coupling member from rotation so that a drill steel section is rotatable relative to said one coupling member to release the joint between adjacent drill steel sections coupled by said one coupling member, and said interlocking means comprising lugs on one of

10 said members which are closely received within notches in the other of said members.

4. In a rock drill having a frame which supports a drill steel centralizer member having open and closed positions which is closed during the starting of drilling to axially guide an elongated sectional drill steel the adjacent sections of which drill steel are joined together by coupling members, respectively, the improvement comprising, locking means on said centralizer member and cooperating locking means on said respective coupling members to provide an interlock between the centralizer member and a selected one of said coupling members when said centralizer member is closed and said locking means are engaged to hold said one coupling member from rotation so that a drill steel section is rotatable relative to said one coupling member to release the joint between adjacent drill steel sections coupled by said one coupling member, and said interlocking means comprising lugs on said centralizer member which are closely received within notches in said coupling members, respectively.

5. In a rock drill having a frame which supports a drill steel centralizer member having open and closed positions which is closed during the starting of drilling to axially guide an elongated sectional drill steel the adjacent sections of which drill steel are joined together by coupling members, respectively, the improvement comprising, locking means on said centralizer member and cooperating locking means on said respective coupling members to provide an interlock between the centralizer member and a selected one of said coupling members when said centralizer member is closed and said locking means are engaged to hold said one coupling member from rotation so that a drill steel section is rotatable relative to said one coupling member to release the joint between adjacent drill steel sections coupled by said one coupling member, and said interlocking means comprising a polygonal socket in said centralizer member in which polygonal portions of said coupling members are received, respectively.

6. In a rock drill having a frame, driving means for driving an elongated sectional drill steel the adjacent sections of which drill steel are joined together by coupling members, respectively, and which frame also supports a centralizer member spaced from such driving means for guiding such drill steel which centralizer member has open and closed positions the improvement comprising, locking means on said centralizer member and cooperating locking means on said respective coupling members to provide an interlock between the centralizer member and a selected one of said coupling members when said centralizer member is closed and said locking means are engaged to hold said one coupling member from rotation so a drill steel section may be rotated relative to said one coupling member for releasing the joint between adjacent drill steel sections coupled by said one coupling member while said rotated drill steel section remains at least partially in supported engagement with said driving means.
